UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Original application filed July 21, 1919, Serial No. 312,346. Divided and this application filed December 11, 1924. Serial No. 755,259.

My invention relates to mining machines. An object of my invention is to provide an improved mining machine. Another object of my invention is to provide an improved mining machine of improved construction and one which is at the same time more flexible in its operation and more conveniently controlled. A further object of my invention is to provide an improved and simplified feeding mechanism for such a machine, said feeding mechanism being operatively connected in an improved manner adapted to improve both the feeding and cutting operations. A still further object of my invention is to provide an improved mining machine adapted to be manufactured at a materially decreased cost and equipped with improved cooperating cutter drive, feeding, and truck driving mechanism operating in an improved manner during cutting, feeding, or transport and controlled by improved controlling mechanisms. Still another object of my invention is to provide an improved mining machine of exceedingly compact form wherein the feeding drums are disposed within the lateral limits of the machine frame. These and other objects and advantages of my invention will, however, hereinafter more fully appear.

In the accompanying drawings I have shown for purposes of illustration one form which my invention may assume in practice.

In these drawings,—

Fig. 1 is a plan view of the mining machine, the feeding and controlling mechanism being shown in section.

Fig. 2 is a transverse vertical sectional view taken substantially on line 2—2 of Fig. 1.

Fig. 3 is a transverse horizontal sectional view taken substantially on line 3—3 of Fig. 2.

Fig. 4 is a detail sectional view taken substantially on line 4—4 of Fig. 1.

Fig. 5 is a diagrammatic view showing the different positions of the machine during the cutting operation in a room or the like.

Fig. 6 is a diagrammatic view similar to that shown in Fig. 5 with the machine cutting in the opposite direction.

In this illustrative disclosure, which is a division of my copending application Ser. No. 312,346, filed July 21, 1919, it will here-

be observed that I have shown a mining machine of the room and pillar type including a frame or casing 1 provided with a bottom plate or shoe 2 adapted to support the machine and slidably upon the mine bottom or a transport truck, not shown, in a well known manner. As shown this frame is provided with a rigid cutter bar 3 as is usual with machines of the type mentioned and this bar carries a cutter chain 4 equipped with cutter bits 5 and rotatable around the bar by means of a cutter chain driving sprocket 6 located within the frame and herein preferably adjacent the rear end thereof through which the cuttings discharge. As illustrated, the machine frame 7 also carries a motor which may be of any suitable type, herein a horizontal longitudinally extending reversible electric motor, having an armature 7 and controlled by any suitable controller mechanisms 8 and 9. The armature 7 of this motor is herein operatively connected through improved mechanism, hereinafter described, to the cutter chain driving sprocket 6 and is also operatively connected, through other improved operative connections likewise hereinafter described, to selectively operative feeding and controlling members 10 and 11, herein in the form of winding drums, and to a truck driving member 12, herein in the form of a chain sprocket, the construction being such that through flexible feeding means, herein for illustrative purposes shown in the form of feeding cables 13 and 14, and operatively connected to the feeding members 10 and 11, respectively, and guided by cooperating guiding members, herein in the form of idler rolls or sheaves 15, 16, and 17, the machine is adapted to be propelled by its own power relative to the mine bottom or to its transport truck, in a well known manner, while through a suitable chain connection, not shown, operatively connectible between the member 12 and the wheels of the transport truck, the machine is adapted to propel the truck when mounted in transport position thereon. It will herein be observed that the guide roll 15 may be transposed to the opposite side of the machine frame when the machine is cutting from left to right.

It will herein further be observed that the motor armature 7 is provided at its rear end with a bevel pinion 19, herein meshing

with a horizontally disposed lower bevel gear 20, which, as shown in Fig. 2, is in turn rotatably mounted in suitable bearings 21 at the upper end of a vertical stud 22 having its lower end thereof extending through suitable adjustable bearings 23 and supported on the shoe 2 at the rear end of the latter. The bevel gear 20 in turn is fixed, herein by a key 24, to a sleeve 25 likewise external to the bearings 21 and coaxially disposed with and rotatable relative to the stud 22 and having a pinion 26 on the lower reduced portion of the sleeve. The pinion 26 meshes with a plurality of slightly larger pinions 27, herein three, disposed radially thereabout and rotatably mounted as on removable bearing members 28 carried on a rotatable spider 29 which, in turn, has an upstanding rotatable sleeve 30 disposed coaxially with the stud 22 and between the same and the pinion 26 and the gear 20. Herein, it will also be observed that the pinions 27 mesh with an internal gear 31, which is journaled on the lower end of the stud 22 and preferably integrally united as by screws 32 with the cutter chain driving sprocket 6 likewise journaled on the stud. The gear 31 is herein also provided with a depending portion 33 having a flange 34 at its periphery running close to the inner edge of a flange 35 formed on the frame 1, the construction being such that the entry of cuttings or the like into the gearing is effectually prevented. Herein, attention is also directed to the fact that the outer periphery 36 of the gear 31 is adapted to be engaged by frictional controlling means, herein in the form of a brake band 37, having one end operatively connected to the frame, as at 38, and its other end connected to a threaded controlling member 39 (see Fig. 4) threaded in the bushing 40 extending through a suitable aperture in the side of the frame and controlled by a nut 43 rotatable by a hand wheel 42 on the outside of the frame. As a result of this construction it will be observed that the cutting chain driving sprocket 6 may be rotated or remain idle while the motor is running, the cutter chain driving sprocket being adapted to be driven at full speed when the member 29 is held stationary.

Operatively connected to the cutter chain driving mechanism is improved cooperating feeding means adapted to drive the feeding and controlling drums 10 and 11. As shown, the sleeve 30 on the spider 29 carries on its upper end a small bevel pinion 45 which, in turn, constantly meshes with corresponding bevel gears 46 and 47. The gears 46 and 47 are herein spaced apart by a spacing and bearing member 48 formed on the upper end of the stud 22 and are freely rotatable on a shaft 50 disposed transversely of the frame, as shown in Fig. 1. Herein the gear 47 is

also suitably rigidly connected, as by a usual semi-permanent clutch or other connecting means 49 to a rotatable driving member 51 herein carrying thereon one of the elements of a friction clutch 52 and cooperating with an outer clutch casing member 53 upon which the drum 10 is formed. The member 53 is in turn journaled, as at 54, in a suitable closure member 55 carried at the side of the machine frame. Herein, the gear 47 has an annular chamber 56 therein receiving an adjustable friction controlling member 57 adapted to compress or release the elements of the friction clutch 52 at will and thereby cause the feeding drum 10 to be rotated with the gear when the friction is loaded or to enable the gear to rotate independently of the drum 10 when the friction is released. Referring back to the gear 46, it will be noted that this gear is similarly connected, as by a usual semi-permanent clutch or other connecting means 58, with a driver member 59 carrying one of the elements of a frictional clutch 60, the other element of the latter being, as heretofore, carried by a casing member 61 upon which the drum 11 is formed. The member 61 is journaled, as at 62, in a closure member 63, similar to the member 55, carried by the opposite side of the machine frame. The gear 46 is likewise provided with an annular chamber 64 therein receiving an adjustable friction controlling member 65 similar to the member 57 adapted to compress or release the elements of the friction clutch 60 at will and likewise thereby cause the feeding drum 11 to be rotated with the gear 46 when the friction is loaded or to enable the gear to rotate independently of the gear 46 when the friction is released. Herein, it will also be observed that through my improved gearing action between the feeding mechanism and the cutter chain when the frictions 52 and 60 are used and the brake band 37 is set, the speed of the feed then obtained, i. e., when the cutter chain is not in operation, is materially greater than the cutting speed obtainable when the brake band 37 is released, i. e., when the cutter chain is in operation.

Operatively connected with the feeding mechanism, herein through the friction clutch mechanism 60, is improved truck driving mechanism adapted operatively to connect or disconnect the truck driving member 12. As shown, this member 12 is provided with a sleeve 66 receivable on a corresponding sleeve 67 on a sleeve member 68 which is suitably fixed, as by a key 69, to the clutch casing member 61 and rotatable with the latter. Here it will also be observed that clutch teeth 70 are provided on adjacent surfaces of the members 12 and 68, and that the member 12 is provided with a suitable mechanism 71, similar to that disclosed in my co-pending application mentioned above, where-

by the member 12 may be forced outwardly relative to the member 68 to disengage the clutch teeth 70 when desired, for instance during the cutting operation or during the 5 truck loading or unloading operation. It is thus possible when the machine is on its transport truck to connect the member 12 to the member 68 and consequently to the casting 61 upon which the drum 11 is formed in 10 such manner as to drive the member 12 at a fast speed through the friction mechanism 60, it of course being understood that during this truck driving operation the brake band 37 is set tight in such manner as to prevent 15 movement of the cutter chain driving sprocket 6.

Cooperating with the friction mechanism, herein above described, is improved means for controlling the same whereby the facility 20 of control is enhanced and the effort required by the operator is materially reduced. These means, as shown herein, are of the pressure fluid type, the annular chambers 56 and 64 in the gear members 47 and 46 being 25 in the form of cylinders and the movable friction controlling members 57 and 65 being in the form of pistons movable in said cylinders under the influence of pressure fluid, herein, pressure liquid such as oil admitted thereto through oppositely located ports 72 and 73 formed in the members 47 and 46 respectively and which communicate with an axial chamber 75 in the shaft 49. It will also be noted that disposed in this chamber 30 75 is a plurality of coaxially and oppositely disposed pistons 76 and 77 provided with operating rods 78 and 79 connected through suitable mechanism, heretofore described in my copending application Ser. No. 312,346, 35 by suitable coaxially arranged hand wheels 80 and 81. By the provision of such a mechanism it will be observed that it is possible to control the frictions substantially as above set forth by adjustment of the hand 40 wheels 80 and 81. More particularly it will be noted that the two pistons 76 and 77 may be simultaneously moved toward one another or away therefrom by adjustment of the hand wheel 81 when the hand wheel 80 is 45 held stationary, and that the rod 79 will be adjusted bodily with the pistons in either direction when the hand wheel 81 is held stationary and the hand wheel 80 is rotated. Thus it will be observed that through movement 50 of the hand wheel 80 the rod 79 may be adjusted bodily to bring the desired piston 76, 77 into full face contact with the oil and thereafter through operation of the hand wheel 81, this desired piston may be adjusted relative to the rod in such manner as to subject the oil to the desired pressure necessary to cause loading of the frictions. Of course both pistons may simultaneously 55 be caused to exert pressure on the oil to effect simultaneous clutch loading, it being possi-

ble by separate or simultaneous adjustments of the hand wheels to produce any desired effect. It will also be noted that the frictions 52 and 60 are provided with suitable load limiting means, generally designated 70 at 82, consequently preventing the feeding members 13 and 14 being overloaded, but as this does not form a part of my present invention and is described and claimed in the above mentioned copending application, further description of the same is deemed unnecessary. It will herein be observed that the cables 13 and 14 extend rearwardly from the drums 10 and 11 through suitable apertures 83 and 84 in the rear end of the frame 80 75 1. It will also be noted that the drums 10 and 11 are located compactly within the lateral limits of the machine frame in such manner as to reduce the width of the latter.

In the operation of my improved mining 85 machine, cutting from right to left as shown in Fig. 5, it will herein be observed that the free end of the cable 13 is secured at the face of the coal by means of a suitable jack A. The clutch 52 controlling the drum 10 90 is then thrown in, winding in the cable 13 at the desired speed and the cutter bar 3 is sumped from the full line position, in under the face of the coal. The receding or controlling cable 14 is then connected adjacent 95 the right hand rib by means of a usual jack or take-up mechanism B and the feed cable 13 is then connected to the jack A which has been moved to the left hand rib. The machine may then be straightened up in any 100 suitable manner, for instance by a roof jack or the take-up B, and by suitable operation of the frictions controlling the drums 10 and 11 the machine is fed transversely across the face, as indicated by the dotted line 105 positions at the right of Fig. 5, the cable 14 maintaining the machine in its straightened position. At the end of the transverse cut the machine is angled relative to the rib, as shown by the dotted line position at the left 110 of Fig. 5, by means of the take up B, by the use of a jack, or by bringing the machine to the desired angle by the drum 11 and then completing the cut. The take-up B may be utilized for angling the machine during the transverse cut, if desired. The machine is then withdrawn from the face by means of the drum 10, in the usual manner. During the cutting operation from left to right, as shown in Fig. 6, the driving motor and the relative position of the cutter bits is reversed and the cable 14 connected to the drum 11, which during this operation is the feeding drum, is connected at the face to the usual jack A. After the sumping cut the cable 13 connected to the drum 10 is connected at the left hand rib by means of a usual jack or take-up mechanism B while the jack A is moved to the right hand rib. The machine is then moved transversely 125 130

across the face and withdrawn from the coal in a manner substantially similar to that described above during the right to left cutting operation shown in Fig. 5. It will herein further be noted that if desired the angle of the machine may be controlled when cutting from right to left, as shown in Fig. 5, by applying the brake band 37 controlling the cutter chain sprocket 6, thereby preventing rotation of the latter, releasing the clutch 52 controlling the drum 10 and applying the clutch 60, and reversing the motor 7, thus causing the controlling drum 11 to act as a take-up member to wind in the cable 14 and thereby pull the rear end of the machine toward the right hand rib. If it is desired to angle the machine when cutting from left to right, as shown in Fig. 6, the brake band 37 may be applied, thus preventing rotation of the sprocket 6, the clutch 60 released and the clutch 52 applied, the motor 7 reversed, and the take-up drum 10 may then wind in the cable 13, pulling the end of the machine toward the left hand rib.

25 As a result of my improved construction a mining machine is provided having improved cutting, feeding means, and controlling mechanism whereby the machine may be operated in opposite directions with greater facility. It will further be noted that improved truck driving mechanism is provided which cooperates directly with the feeding mechanism. It will further be noted that a feeding and cutting mechanism of 30 exceedingly simple and compact character is provided whereby the facility of operation of the cutting and feeding mechanism is substantially increased and wherein the lateral limits of the machine are substantially decreased. These and other objects and advantages of my improved mining machine will be clearly apparent to those skilled in the art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

55 1. In a mining machine, feeding mechanism including a shaft, a feed member and a controlling member each disposed coaxially with said shaft, said feed and controlling members being relatively rotatable and 60 each adapted to cooperate directly with flexible feeding means during machine feeding and to cooperate in effecting guided movements of the machine, and friction means operable to effect simultaneous independent control of said members.

2. In a mining machine, feeding mechanism including a feed operating member and a controlling member each of which is adapted to cooperate directly with flexible feeding means, and means including a separate friction controlling clutch for each of said members to effect simultaneous rotation of said members at the same speed in opposite directions.

3. In a mining machine, feeding mechanism including a feed operating member and a controlling member having separate flexible feeding elements cooperating therewith, and means including a separate friction controlling clutch for each member to simultaneously rotate said members in opposite directions to respectively wind in and pay out said elements each at a predetermined slow speed.

4. In a mining machine, feeding mechanism including a shaft, a plurality of coaxial relatively rotatable feeding members each adapted to cooperate directly with flexible feeding means, and a plurality of friction clutches arranged coaxially with said shaft for independently controlling said members, one of said clutches being individual to the control of one of said members and the other to the control of the other.

5. In a mining machine, a machine frame 95 100 105 110 115 120 125 130 135 140 145 150 155 160 165 170 175 180 185 190 195 200 205 210 215 220 225 230 235 240 245 250 255 260 265 270 275 280 285 290 295 - slidable on the mine bottom, cutting mechanism carried thereby including an elongated plane cutter bar, and mechanism for feeding said cutter bar laterally comprising a shaft, coaxial feeding drums disposed thereon, a plurality of friction clutches disposed within said drums for controlling the operation of the same, and means arranged coaxially with said drums for simultaneously 5 or independently controlling said clutches.
10. In a mining machine including a machine frame, cutting mechanism carried thereby including an elongated plane cutter bar, and mechanism for feeding said cutter bar laterally including a feed operating drum and a controlling drum disposed within said machine frame, and controlling means for said drums arranged coaxially therewith.
15. 11. In a mining machine including a machine frame, cutting mechanism carried thereby including an elongated plane cutter bar, and mechanism for feeding said cutter bar laterally including a feed operating 20 drum and a controlling drum disposed within the limits of said frame, cables cooperating with said drums, and controlling means for said drums arranged coaxially therewith.
25. 12. In a mining machine, a machine frame, cutting mechanism carried thereby including an elongated plane cutter bar, and mechanism for feeding said cutter bar laterally including a horizontally disposed relatively rotatable feed operating shaft, and controlling members disposed coaxially therewith and each adapted to cooperate directly with flexible feeding means, and friction means operative to independently control 30 said members.
35. 13. In a mining machine, a horizontally disposed shaft, coaxial feeding drums disposed thereon, a plurality of friction clutches disposed within said drums for controlling the operation of the same, and means arranged coaxially with said drums for simultaneously or independently controlling said clutches.
40. 14. In a mining machine, feeding mechanism including a shaft, feed and controlling members disposed coaxially therewith each adapted to cooperate with flexible feeding means, and hydraulic means for controlling said members.
45. 15. In a mining machine, feeding mechanism including a shaft, feed and controlling members disposed coaxially therewith each adapted to cooperate with flexible feeding means, and hydraulic means for controlling 50 said members disposed within said shaft.
55. 16. In a mining machine, feeding mechanism including a shaft, feed and controlling members disposed coaxially therewith each adapted to cooperate with flexible feeding means, and a plurality of hydraulically 55
- operative friction clutches for controlling said members.
17. In a mining machine, a feed operating member and a controlling member each adapted to cooperate directly with flexible feeding means, driving means therefor including a pair of frictions disposed coaxially with said members, and means for simultaneously driving said members in opposite directions at the same speed.
18. In a mining machine, a feed operating member and a controlling member each adapted to cooperate directly with flexible feeding means, driving means therefor including a pair of frictions disposed coaxially with said members, and means for simultaneously driving said members in opposite directions at variable speeds.
19. In a mining machine, feeding means including a feed operating member, a controlling member, said members each being adapted to cooperate with flexible feeding means, frictionally controlled feeding mechanism therefor including a plurality of frictions, and pressure fluid actuated controlling 60 means for each of said frictions.
20. In a mining machine, a frictionally controlled feeding mechanism including a plurality of frictions, a feeding member and a controlling member driven thereby, said members each being adapted to cooperate with flexible feeding means, and hydraulic controlling means adjustable to control either or both of said frictions.
21. In a mining machine, frictionally controlled feeding mechanism including a plurality of frictions, a feeding member and a controlling member, said members each being adapted to cooperate with flexible feeding means, and pressure fluid actuated controlling means operative to apply either of said frictions separately or both simultaneously including a plurality of independently operable controlling members.
22. The combination with a mining machine, of feeding mechanism including a feed operating member and a controlling member, said members each being adapted to cooperate with flexible feeding means and being relatively rotatable, cutting mechanism, and reaction driving mechanism between said feeding mechanism and said cutting mechanism.
23. The combination with a mining machine, of feeding mechanism including a feed operating member and a controlling member, said members each being adapted to cooperate with flexible feeding means and being relatively rotatable, cutting mechanism, and variable reaction driving mechanism between said feeding mechanism and said cutting mechanism.
24. The combination with a mining machine, of feeding mechanism including a feed operating member and a controlling mem-

ber, said members each being adapted to cooperate with flexible feeding means, cutting mechanism, and mechanical means operatively connecting the same for decreasing the speed of one upon an increase in speed of the other.

25. The combination with a mining machine, of feeding mechanism including a feed operating member and a controlling member, said members each being adapted to cooperate with flexible feeding means, cutting mechanism, and variable speed mechanism between said feeding mechanism and said cutting mechanism to cause the speeds of said members and said cutting mechanism to vary inversely.

26. In a mining machine, the combination including a motor, a feed operating member and a controlling member each adapted to cooperate directly with flexible feeding means, cutting mechanism, and variable speed mechanism between said cutting mechanism and said members driven by said motor and operative to cause the speeds of said members and said cutting mechanism to vary inversely proportionally while the motor speed remains substantially constant.

27. The combination with a mining machine, cutting mechanism, feeding mechanism including a feed operating drum and a controlling drum, and feed gearing associated therewith directly controlled by the reaction of said cutting mechanism.

28. In a mining machine, feeding mechanism including a feed operating friction clutch, a takeup friction operating clutch, and a supplemental clutch adjustable at will to retard either of said clutches to vary the feed accomplished thereby.

40 29. In a mining machine, feeding mechanism including a frictional feed device and a frictional takeup device, and a cooperating frictional device adapted to retard said feed and takeup frictional devices to vary the rate of feed of said machine.

30. In a mining machine, feeding mechanism including a frictional feed device, a frictional takeup device, and a cooperating frictional device adjustable at will and adapted to vary the effect of both said feed and takeup frictional devices.

55 31. The combination with a mining machine having cutting mechanism including a cutter chain carrying cutter bar and means for effecting circulation of said chain in opposite directions relative to said bar to cut and clear a kerf during lateral feeding in either direction, a feeding mechanism for propelling the same laterally along a face in either direction during cutting including a plurality of feed operating members respectively adapted to propel the machine laterally during opposite directions of operation of the cutting mechanism, flexible feeding

60 65 means including flexible feeding portions in

either direction of feed extending in opposite directions from the opposite ends of the frame and when feeding in different directions having different portions forming the advance portion and wound in by different feed operating members to which they are respectively individual, and actuating and controlling means for said feed operating members carried on said machine operative to permit paying out of one of said portions at a different rate from that at which the other is wound in.

32. The combination with a mining machine having cutting mechanism including a cutter chain carrying cutter bar and means for effecting circulation of said chain in opposite directions relative to said bar to cut and clear a kerf during lateral feeding

80 either direction, a feeding mechanism for propelling the same laterally along a face in either direction during cutting including a plurality of feed operating members respectively adapted to propel the machine laterally during opposite directions of operation

85 of the cutting mechanism, flexible feeding means including flexible feeding portions in either direction of feed extending in opposite directions from the opposite ends of the frame and when feeding in different directions having different portions forming the

90 advance portion and wound in by different feed operating members to which they are respectively individual, and actuating and controlling means for said feed operating members carried on said machine operative

95 to permit paying out of one of said portions at a faster rate than that at which the other is wound in.

33. In combination, in a mining machine having cutting mechanism including a cutter chain carrying cutter bar provided with a circulating cutter chain operative when propelled in opposite directions relative to said bar to cut and clear a kerf during lateral feeding in opposite directions, a motor and

100 means for propelling said machine in opposite directions across a mine face during cutting in opposite directions including a pair of like relatively rotatable feed operating members rotating on horizontal axes at op-

105 posite sides of said machine frame and each adapted to cooperate directly with flexible feeding means, and actuating and controlling means therefor driven by said motor in-

110 cluding a driving member rotated in opposite directions on reversal of said motor and means for operatively connecting either of

115 said feed operating members thereto for driving thereby.

34. In combination, in a mining machine having cutting mechanism including a cutter chain carrying cutter bar provided with a circulating cutter chain operative when propelled in opposite directions relative to

120 said bar to cut and clear a kerf during lat-

125

130

eral feeding in opposite directions, a motor and means for propelling said machine in opposite directions across a mine face during cutting in opposite directions including a pair of relatively rotatable like feed operating members rotating on transversely extending axes at opposite sides of said machine frame and each adapted to cooperate directly with flexible feeding means, and actuating and controlling means therefor driven by said motor including a member rotated in opposite directions on reversal of said motor and means for operatively connecting either of said feed operating members thereto for driving thereby.

35. In a mining machine, the combination including reversible cutting mechanism including a cutter chain having reverse cutting elements operative on driving of said chain in reverse directions to cut and clear a kerf when said machine is propelled in opposite directions across a face and a cutter chain driving sprocket cooperating with said cutter chain to actuate the same, a motor disposed in advance of said cutter chain driving sprocket, and means for propelling said machine at equal speeds in opposite directions during cutting across a face including a plurality of relatively rotatable like feed operating members rotatable on horizontal transversely extending axes at opposite sides of the machine frame to the rear of said motor and each adapted to cooperate directly with flexible feeding means, and means driven by said motor for actuating said feed operating members including a shaft to the rear of said motor and means for selectively connecting said feed operating members in driven relation to said shaft.

40 36. In a mining machine, the combination including reversible cutting mechanism including a cutter chain having reverse cutting elements operative on driving of said chain in reverse directions to cut and clear
45 a kerf when said machine is propelled in opposite directions across a face and a cutter chain driving sprocket cooperating with said cutter chain to actuate the same, a motor disposed in advance of said cutter chain
50 driving sprocket, and means for propelling said machine at equal speeds in opposite directions during cutting across a face including a plurality of relatively rotatable like feed operating members rotatable on horizontal transversely extending axes at opposite sides of the machine frame to the rear of said motor and each adapted to cooperate directly with flexible feeding means, and means driven by said motor for actuating
55 said feed operating members including a shaft to the rear of said motor and means for selectively connecting said feed operating members in driven relation to said shaft including clutch means slidably transversely of said machine.

37. In a mining machine, the combination including reversible cutting mechanism including a cutter chain having reverse cutting elements operative on driving of said chain in reverse directions to cut and clear a kerf when said machine is propelled in opposite directions across a face and a cutter chain driving sprocket cooperating with said cutter chain to actuate the same, a motor disposed in advance of said cutter chain driving sprocket, and means for propelling said machine at equal speeds in opposite directions during cutting across a face including a plurality of relatively rotatable like feed operating members rotatable on horizontal transversely extending axes at opposite sides of the machine frame to the rear of said motor and each adapted to co-operate directly with flexible feeding means, and means driven by said motor for actuating said feed operating members including a shaft to the rear of said motor and means for selectively connecting said feed operating members in driven relation to said shaft including clutch means at opposite sides of the center line of said machine and reciprocable transversely of the machine to connect the elements operatively controlled thereby in driven relation to said shaft. 70 75 80 85 90 95

38. The combination with a mining machine having reversible cutting mechanism, of feeding mechanism for propelling the same laterally along a face in either direction during cutting including a plurality of relatively rotatable feed operating members each adapted to propel the machine laterally during a different direction of operation of said cutting mechanism, and flexible feeding means including flexible feeding portions in either direction of feed extending in opposite directions from the opposite ends of said frame and when feeding in different directions having different portions forming the advance portion and wound in by different feed operating members to which they are respectively individual. 105 110

39. The combination with a mining machine having reversible cutting mechanism, of feeding mechanism for propelling the same laterally along a face in either direction during cutting including a plurality of relatively rotatable feed operating members rotatable on transverse axes on opposite sides of said machine frame each adapted to propel the machine laterally during a different direction of operation of said cutting mechanism, and flexible feeding means including flexible feeding portions in either direction of feed extending in opposite directions from the opposite ends of said frame and when feeding in different directions having different portions forming the advance portion and wound in by different feed operating members to which they are respectively individual. 115

40. The combination with a mining machine having reversible cutting mechanism, of feeding mechanism for propelling the same laterally along a face in either direction during cutting including a plurality of relatively rotatable feed operating members of the same size each adapted to propel the machine laterally during a different direction of operation of said cutting mechanism, 10 and flexible feeding means including flexible feeding portions in either direction of feed extending in opposite directions from the opposite ends of said frame and when feeding in different directions having different 15 portions forming the advance portion and wound in by different feed operating members to which they are respectively individual.

41. The combination with a mining machine having reversible cutting mechanism, of feeding mechanism for propelling the same laterally along a face in either direction during cutting including a plurality of relatively rotatable feed operating members of the same size rotatable on transverse axes on opposite sides of said machine frame each adapted to propel the machine laterally during a different direction of operation of said cutting mechanism, and flexible feeding means including flexible feeding portions in either direction of feed extending in opposite directions from the opposite ends of said frame and when feeding in different directions having different 35 portions forming the advance portion and wound in by different feed operating members to which they are respectively individual.

42. The combination with a mining machine having reversible cutting mechanism, of feeding means therefor including a plurality of relatively rotatable feed operating members of the same size respectively adapted to propel the machine laterally in opposite directions, flexible feeding means including a plurality of flexible feeding portions one individual to each of said feed operating members, and guiding means for said portions, said feed operating members rotating in opposite directions depending upon the direction of rotation of said cutting mechanism.

43. The combination with a mining machine slideable on a mine bottom and having reversible cutting mechanism, of flexible lateral feeding mechanism therefor including a plurality of relatively rotatable cable drums, a plurality of flexible feeding members, one individual to and wound on each of said drums and disposable laterally, and guiding means disposed on said machine and cooperating with said flexible feeding members, said mechanism having provision for feeding said machine laterally in opposite directions under the propulsion of

different drums and during operation of said cutting mechanism in opposite directions and provision whereby during opposite lateral feeding movements either of said flexible feeding members may act as the advancing member while its fellow acts as the receding member.

44. The combination with a mining machine slideable on a mine bottom and having reversible cutting mechanism, of flexible lateral feeding mechanism therefor including a plurality of relatively rotatable cable drums disposed on transverse axes on opposite sides thereof, a plurality of flexible feeding members, one wound on and individual to each of said drums and disposable laterally, and guiding means disposed on said machine and cooperating with said flexible feeding members, said mechanism having provision for feeding said machine laterally in opposite directions under the propulsion of different drums and during operation of said cutting mechanism in opposite directions and provision whereby during opposite lateral feeding movement either of said flexible feeding members may act as the advancing member while its fellow acts as the receding member.

45. The combination with a mining machine slideable on its bottom on a mine bottom and having reversible cutting mechanism, of flexible lateral feeding means therefor including a plurality of relative rotatable cable drums of the same diameter and rotatable on transverse axes and disposed on opposite sides of said machine, a plurality of flexible feeding members each cooperating with and individual to one drum and disposable laterally, and guiding means cooperating with each flexible feeding member, said mechanism having provision for feeding said machine laterally in opposite directions under the propulsion of different drums and during operation of said cutting mechanism in opposite directions and provision whereby during opposite lateral feeding movements either flexible feeding member may act as either the advance or receding member while its fellow acts as the receding or advance member.

46. The combination with a mining machine slideable on a mine bottom and having reversible cutting mechanism, of flexible lateral feeding mechanism therefor including a plurality of relatively rotatable cable drums, a plurality of flexible feeding members, one individual to and wound on each of said drums and disposable laterally, and guiding means disposed on said machine and cooperating with said flexible feeding members, said mechanism having provision for feeding said machine under the propulsion of different drums laterally in opposite directions at the same speed during operation of said cutting mechanism in opposite di-

rections and provision whereby during opposite lateral feeding movements either of said flexible feeding members may act as the advancing member while its fellow acts as the receding member.

47. The combination with a mining machine slideable on a mine bottom and having reversible cutting mechanism, of flexible lateral feeding mechanism therefor including 10 a plurality of relatively rotatable cable drums disposed on transverse axes on opposite sides thereof, a plurality of flexible feeding members, one individual to and wound on each of said drums and disposed 15 laterally, and guiding means disposed on said machine and cooperating with said flexible feeding members, said mechanism having provision for feeding said machine under the propulsion of different drums laterally in opposite directions at the same speed during operation of said cutting mechanism in opposite directions and provision whereby during opposite lateral feeding movements either of said flexible feeding members may act as the advancing member while its fellow acts as the receding member.

48. The combination with a mining machine slideable on its bottom on a mine bottom 30 and having reversible cutting mechanism, of flexible lateral feeding means therefor including a plurality of relatively rotatable cable drums of the same diameter and rotatable on transverse axes and disposed on opposite sides of said machine, a plurality of flexible feeding members each cooperating with and individual to one drum and disposable laterally, and guiding means cooperating with each flexible feeding member, said mechanism having provision for feeding said machine under the propulsion of different drums laterally in opposite directions at the same speed during operation of said cutting mechanism in opposite directions and provision whereby during opposite lateral feeding movements either flexible feeding member may act as either the advance or receding member while its fellow acts as the receding or advance member.

50. 49. The combination with a mining machine slideable on a mine bottom and having reversible cutting mechanism including a rigid stationary cutter bar and a rotatable cutter chain thereon, of flexible lateral feeding mechanism therefor including a plurality of relatively rotatable cable drums, a plurality of flexible feeding members one wound on each of said drums and individual thereto and disposable laterally, and guiding means disposed on said machine and cooperating with said flexible feeding members, said mecha-

nism having provision for feeding said machine under the propulsion of different drums, laterally in one direction during rotation of said cutter chain in one direction and in the opposite direction during rotation of said chain in the opposite direction and provision whereby during lateral feeding in different directions a different flexible feeding member acts as the advancing member while its fellow acts as the receding member.

50. The combination with a mining machine slideable on a mine bottom and having reversible cutting mechanism including a rigid stationary cutter bar and a rotatable cutter chain thereon, of flexible lateral feeding mechanism therefor including a plurality of relatively rotatable cable drums disposed on transverse axes on opposite sides thereof, a plurality of flexible feeding members one wound on and individual to each of said drums and disposable laterally, and guiding means disposed on said machine and cooperating with said flexible feeding members, said mechanism having provision for feeding said machine under the propulsion of different drums laterally in one direction during rotation of said cutter chain in one direction and in the opposite direction during rotation of said chain in the opposite direction and provision whereby during lateral feeding in different directions a different flexible feeding member acts as the advancing member while its fellow acts as the receding member.

51. The combination with a mining machine slideable on a mine bottom and having reversible cutting mechanism including a rigid stationary cutter bar and a rotatable cutter chain thereon, of flexible lateral feeding mechanism therefor including a plurality of relatively rotatable cable drums of the same diameter, rotatable on transverse axes, and disposed on opposite sides of said machine, a plurality of flexible feeding members one wound on and individual to each of said drums and disposable laterally, and guiding means disposed on said machine and cooperating with said flexible feeding members, said mechanism having provision for feeding said machine under the propulsion of different drums laterally in one direction during rotation of said cutter chain in one direction and in the opposite direction during rotation of said cutter chain in the opposite direction and provision whereby during lateral feeding in different directions a different flexible feeding member acts as the advancing member while its fellow acts as the receding member.

In testimony whereof I affix my signature.
MORRIS P. HOLMES.

CERTIFICATE OF CORRECTION.

Patent No. 1,662,794.

Granted March 13, 1928, to

MORRIS P. HOLMES.

It is hereby certified that error appears in the printed specification of the above numbered patent requiring correction as follows: Page 1, line 19, for the word "mechanism" read "mechanisms"; page 2, line 30, for the word "is" read "its"; line 64, for the number "50" read "49", and line 68, for the number "49" read "50"; page 5, line 35, claim 12, strike out the word "shaft" and insert the same to follow after the word "disposed" in line 34; page 8, line 98, claim 45, for the word "relative" read "relatively"; page 9, line 63, claim 49, after the word "drums" strike out the comma; and that the said Letters Patent should be read with these corrections therein that the same may conform to the record of the case in the Patent Office.

Signed and sealed this 1st day of May, A. D. 1928.

(Seal)

M. J. Moore,
Acting Commissioner of Patents.
